Inventor:

T. J. Mayall

UNITED STATES PATENT OFFICE.

THOMAS J. MAYALL, OF ROXBURY, MASSACHUSETTS.

IMPROVED PONTON.

Specification forming part of Letters Patent No. 40,421, dated October 27, 1863.

To all whom it may concern:

Be it known that I, THOMAS J. MAYALL, of Roxbury, in the county of Norfolk and State of Massachusetts, have invented certain new and useful Improvements in Ponton-Bridges; and I do hereby declare that the following description, taken in connection with the accompanying drawings, hereinafter referred to, forms a full and exact specification of the same, wherein I have set forth the nature and principles of my said improvements by which my invention may be distinguished from all others of a similar class, together with such parts as I claim and desire to have secured to me by Letters Patent.

The figures of the accompanying plate of drawings represent my improvements.

Figure 1 is a plan or top view; Fig. 2, a central longitudinal vertical section, and Fig. 3 a central transverse vertical section.

The present invention consists in certain new and useful improvements in the construction of boats or vessels with a view to facilitate their transportation over land, and yet be quickly and easily put in readiness to be launched.

My new boats are designed to be used mostly for army purposes for the transportation of material of war and for the formation of ponton-bridges; although they are equally well adapted to any use which requires both carrying capacity or buoyancy on water and lightness and compactness for land travel.

I construct a boat according to my improvements as follows: I take a sheet or sheets of flexible water-proof material, *a a a a*, like india-rubber, or cloth-coated with the same or with any other water-proof substance, and form the same into the required shape and size to constitute the body of the boat. In and around the edges of this body or bottom of the boat I form a series of grummet-holes, *b b*, &c., protected by suitable eyelets. *c c* is a frame, made rigid, to which the flexible body *a a a a* is secured by means of pins, bolts, chains, or cords passing through the grummet-holes *b b*, &c., and through corresponding holes, *d d*, &c., formed in the frame *c c*. Thus it will be seen the gunwales of the boat are formed.

To bring the flexible body *a a a a* into the required boat shape, I have arranged the following devices: To the frame *c c* is attached

by a suitable hinge or pivot two or more swinging frames, *e e e e*, of the shape shown in the drawings. When they are depressed so as to occupy a vertical position, as shown in Figs. 2 and 3, the flexible body *a a a a* is distended into the required shape and rigidly held in this condition. To keep the swinging frames *e e e e* firmly in a vertical position any suitable locking device may be used. To still further increase the stiffness of the boat I employ longitudinal braces or bars *J J* in the bottom thereof, against which the swinging frames *e e e e* bear, as shown in Figs. 2 and 3. When the boat is to be transported over land, the swinging frames *e e e e* are raised into a horizontal position, so as to be parallel with the gunwale-frame *c c* and the longitudinal braces or bars are removed. Then it will be seen the body *a a a a* being flexible, the whole can be packed in a very small space.

From the foregoing description it will be seen that the flexible body *a a a a* can be almost instantaneously put into such a compact form as to be easily transported from place to place and as quickly formed into a boat for the conveyance of persons, animals, or goods on the water.

The frame *c c* can be constructed so as to be dismembered by forming screw or other joints at the corners, and the whole boat by turning upside down and providing proper base supports thereto can be used as a shelter-tent.

A series of these boats side by side, or otherwise, will, it will be obvious, form a buoyant and substantial ponton-bridge, by simply placing any suitable planking to form a roadway across them.

Having thus described my improvements, what I claim as my invention, and desire to have secured by Letters Patent, is—

1. The distending boat-frame, the same consisting of a main frame and one or more swinging frames, the whole being constructed to operate together as described.
2. In combination with the main and swinging frames, constituting a distending frame, operating substantially as set forth, the longitudinal braces, arranged as herein described, for stiffening the bottom as specified.

THOS. J. MAYALL.
